United States Patent Office.

FREDERICK A. GEISLER, OF BRISTOL, RHODE ISLAND.

Letters Patent No. 82,304, dated September 22, 1868.

IMPROVED BABY-WALKER.

The Schedule referred to in these Letters Patent and making part of the same.

TO ALL WHOM IT MAY CONCERN:

Be it known that I, FREDERICK A. GEISLER, of Bristol, in the county of Bristol, and State of Rhode Island, have invented a new and useful Improvement in Baby-Walkers; and I do hereby declare that the following is a full, clear, and exact description thereof, which will enable others skilled in the art to make and use the same, reference being had to the accompanying drawings, forming part of this specification, in which—

Figure 1 represents a plan view of my improved apparatus.

Figure 2 represents a sectional elevation of the same, and

Figure 3 represents a detail view.

Similar letters of reference indicate like parts.

This invention relates to an improvement in baby-walkers; and it consists in the construction of the yoke or holder whereby it is made adjustable.

A represents a circular platform, having a central vertical shaft, B, adjustably supported by the set-screw C. D represents a shaft, arranged to rotate on the shaft B, and provided with a spring-pawl, E, which takes into notches in the enlarged upper portion of the shaft B, for the purpose of preventing the shaft D from moving backwards. The notches are so formed as to readily admit the shaft to move forward.

The spring-pawl is let into a recess in the shaft D, and otherwise so arranged that the child or its dress cannot be caught in the pawl, or the pawl be inadvertently displaced from the ratchet.

The upper end of the shaft D is provided with a curved arm, F, at the outer end of which the supporting-yoke G is connected, in such a manner as to allow it to oscillate to some extent in a horizontal plane, for the purpose of allowing the child more freedom than he otherwise would have.

The said yoke may be made in two parts, *a* and *b*. The part *a*, which is connected to the arm F by the bolt *d*, is provided with a socket, and the part *b* with a shank, fitting into the said socket, and the two secured together by a set-screw, *c*.

By this arrangement a simple and reliable apparatus is afforded, in which the child may have great freedom of action without danger to itself.

Having thus described my invention, I claim as new, and desire to secure by Letters Patent—

The oscillating yoke G, made in two parts, *a* *b*, the former pivoted by the bolt *d* to the curved arm F, and provided with a socket, in which the shank of the arm *b* is adjusted by the set-screw *c*, as herein described for the purpose specified.

FREDERICK A. GEISLER.
